FEEDING MECHANISM FOR ROCK DRILLS

John C. Curtis, Garfield Heights, Ohio, assignor
to The Cleveland Rock Drill Company, Cleve-
land, Ohio, a corporation of Ohio

Application February 2, 1933, Serial No. 654,802

6 Claims. (Cl. 121—9)

This invention relates broadly to rock drills, but more particularly to feeding mechanism for rock drills of the drifter type.

One of the objects of this invention is to provide 5 a rock drill with an improved feeding mechanism of simple design and economic of manufacture.

Another object of this invention is to provide a 10 rock drill with a feeding mechanism transmitting forward and rearward motion to the drill at a uniform rate of power, but at a greater rate of speed than that of the feeding element.

Other objects and advantages more or less ancillary to the foregoing and the manner in which the various objects are attained, reside in 15 the specific construction and aggroupment of the elements peculiar to this structure, as will become apparent from a more complete examination of this specification, in the claims of which there are assembled certain specific combinations of 20 parts and specific constructions indicative of the scope and spirit of the invention.

In the drawings which illustrate a preferred 25 embodiment of the invention.

Fig. 1 is a longitudinal view, partly in section, 25 of the machine assembly.

Fig. 2 is an enlarged cross sectional view taken in a plane indicated by line 2—2 in Fig. 1.

Fig. 3 is an enlarged cross sectional view taken in a plane indicated by line 3—3 in Fig. 2.

30 Fig. 4 is an enlarged view of a portion of the front end of the feed tube illustrating the manner in which the tension of the chain may be adjusted.

Fig. 5 is an enlarged sectional view of the feed 35 tube partition shown in Fig. 1.

Fig. 6 is an enlarged view illustrating how the ends of the chain are fastened to the feed tube.

Fig. 7 is an enlarged view of the backhead secured to one end of the feed tube.

40 Figs. 8 and 9 are cross sectional views taken in a plane indicated by line 8—8 in Fig. 7, illustrating the throttle valve in different positions.

Referring to the drawings in which like symbols designate corresponding parts throughout 45 the several views, 10 represents a rock drill or drilling motor capable to deliver blows to a drill steel 11. The rock drill has its lower wall formed with a pair of longitudinally disposed ribs 12, capable of slidable engagement with the guides 13, 50 which are disposed on the upper wall of a rock drill support 14. This support is formed of a rectangular tubular member constituting a feed tube 15, having attached to its lower external wall a cone 15', by which the support may be secured 55 to any appropriate frame. Disposed within the

feed tube 15, there is a member or partition 16 secured therein by bolts 17. This partition is located to divide the tube 15 in two substantially equal portions 18 and 19. The partition 16 is formed with a centrally disposed bore having secured therein a member 20 formed with an enlarged head 21 which extends into the feed tube portion 18. The member 20 is internally threaded to receive a member 22 which is also formed with an enlarged head 23 extending into the feed 10 tube portion 19. Clamped between the heads 21 and 23, on each side of the partition 16, there is a packing 24 and 25, capable of fluid tight engagement with the internal wall of the feed tube 15. Formed within the heads 21 and 23 of the members 20 and 22, there is an enlarged cavity or bore 26 and 27, the purpose of which will be explained hereafter. Leading from the bore 26 into the bore 27, there is an aperture within which there is reciprocably mounted a rod 28. Circumventing 20 this rod and capable of fluid tight engagement therewith, there are V-shaped packings 29 and 30, which are disposed in opposite direction into grooves formed within the members 20 and 22.

The end portions 31 and 32 of the rod 28 are 25 restricted in diameter to form shoulders 33. Mounted on the restricted portion 31, there is a piston 34 comprising a packing 35 in fluid tight engagement with the internal wall of the feed tube 15, and a retainer 36 having its longitudinal 30 movement limited by its engagement against the shoulder 33. Clamped against the piston 34, there is a bracket 37 which is secured thereon by a nut 38, in screw tight engagement with the end 35 of the restricted portion 31. Mounted in the restricted portion 32, there is a piston 39, comprising a packing 40 and retainer 41. A bracket 42 is also clamped against the piston 39 by a nut 43. The retainers 36 and 41 are properly machined for close fit engagement into the bores 26 and 27 40 of the members 21 and 23. The brackets 37 and 42 are conveniently machined to receive the sprockets 44 and 45, rotatably mounted on a transversally disposed shaft 46.

The right end of the tube 15, hereafter designated as the front end of the tube, is closed by a front head 47 secured therein by means of bolts or the like. Disposed on the lower wall of the feed tube 15, adjacent the front head 47, there is secured a member 47' formed with a plurality 50 of equally spaced bores 48, located on a plane coinciding with the vertical plane passing through the middle of the sprocket 44. Pressed within these bores, there are pins 49 having a restricted portion protruding therefrom and capable to re- 55

ceive between them the rollers 50 of one end of a chain 51. Held in engagement with the top of the pins 49 by means of bolts 52, there is a plate 53 preventing the accidental disengagement of the chain 51 with the pins 49, and simultaneously maintaining the pins 49 within the bores 48.

The upper front end portion of the feed tube 15 is properly machined to receive on each side thereof a bracket 54 having a slot 55 through which bolts 56 are disposed for securing the brackets to the tube. Rotatably mounted between these brackets, there is a sprocket 57 which protrudes to the exterior of the tube 15 through a slot 58.

The rear end of the feed tube 15 is closed by a backhead 59 secured thereto by means of bolts or the like. Disposed on the lower internal wall of the feed tube 15, adjacent the backhead 59, there is secured a member 59' formed in a manner similar to the member 47', for the purpose of securing the other end of the chain 51. The upper rear end portion of the feed tube 15 is conveniently machined to receive a sprocket 60, rotatably mounted on a transversally disposed shaft 61. This last sprocket protrudes to the exterior of the feed tube 15 through a slot 62.

Rotatably mounted within the backhead 59, there is a throttle valve 63, which may be actuated by means of a handle 64. Centrally disposed within this throttle valve, there is an enlarged bore 65, into which pressure fluid may be admitted from its source of supply. Leading from the bore 65, there are two radially disposed passages 66 and 67. Formed on the external wall of the throttle valve, between the passages 66 and 67, there is a groove 68 in constant communication with the vent hole 69. The passage 66 is capable of communication with the portion 18 of the feed tube 15, through a restricted conduit 71, which opens into the feed tube adjacent the partition 16. The passage 57 may similarly be in communication with the portion 19 of the feed tube 15, through a restricted conduit 70, opening therein adjacent the partition 16.

The chain 51, having one of its ends attached to the front head 47, and the other to the backhead 59, is of sufficient length to pass under the sprocket 44, then over the adjustable sprocket 57, stationary sprocket 60, and back under the reciprocable sprocket 45. At a point substantially equally distant from the ends of the chain, the latter is attached to the rock drill by means of a plug 72. This plug is secured to the rock drill into an apertured lug 73 which extends downwardly from the lower wall thereof. The plug 72 is formed with a head 74 capable of engagement with the one side of the wall of the lug, and has its other end provided with an eccentrically located restricted portion 75, threaded to receive a nut 76. The upper portion of the plug 72 is formed with teeth 77 capable of engagement with the chain 51. To permit the free passage of the chain under the rock drill, the latter is formed with a longitudinally disposed groove 78.

In the operation of the mechanism, assuming the throttle valve 63 to be positioned as illustrated in Fig. 9. Pressure fluid is admitted from the throttle valve bore 65 into the feed tube portion 18, through the valve passage 66 and conduit 71. Pressure fluid admitted into that portion of the feed tube will act on the piston 39 to move the latter rearwardly. Simultaneously the feed tube portion 19 is vented to the atmosphere

through the conduit 70, valve groove 68, and vent hole 69, thus permitting the rearward movement of the piston 34 and consequently the rearward movement of the piston 39, since these pistons are united by the rod 28. During the rearward movement of the pistons, the chain 51 passing under the sprocket 44, will cause the forward movement of the rock drill 10. Due to the association of the chain 51 with the sprocket 44, which moves rearwardly with the piston, the chain 51 will pull the rock drill forwardly at a double rate of speed than that of the piston 34. The speed of the piston and consequently the speed of feed transmitted by the chain 51 to the rock drill 10, may be regulated by a more or less complete registration of the passage 66 with the conduit 70, thus varying the amount of pressure fluid admitted into the feed tube.

Toward the end of the rearward stroke of the pistons 34 and 39, the retainer 36 will enter the bore 27 of the member 23, thus compressing the atmosphere therein to create an air cushion for checking the impact of the piston 34 against the partition 16.

When it is desired to retract the drilling motor 25 from the work, the throttle valve 63 may be positioned as illustrated in Fig. 8. In this instance pressure fluid is admitted into the portion 19 of the feed tube 15, through the throttle valve passage 67 and conduit 70. The pressure fluid in that portion of the feed tube will act on the piston 34 to move the latter, together with the piston 29, forwardly. Simultaneously the feed tube portion 18 is vented to the atmosphere through the conduit 71, throttle valve groove 68 and vent hole 69.

From the foregoing, it will be seen that since the areas of the pistons subjected to the pressure fluid are equal, the speed of the forward movement of the rock drill is equal to the speed of its rearward movement. Consequently, even though the rate of feeding speed transmitted to the drill is greater than that of the feed pistons, the feeding power transmitted to the drill remains constant irrespective of the sense of travel of the latter.

Pressure fluid admitted into the feed tube 15 will act on the packings 35 and 25 or 40 and 24, to assure a fluid tight joint of the different members therein with the internal wall of the feed tube 15. Similarly any pressure fluid tending to escape around the rod 28 from one side of the partition 16 to another, will be arrested by the action of the packings 29 or 30.

The tension of the chain 51 may be adjusted, by simply loosening the bolts 56 and sliding the bracket 54, which carry the sprocket 57, into any desired position.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

I claim:

1. In a rock drilling apparatus, a support having a drilling motor slidably guided thereon, a feeding mechanism for said motor comprising a tube having a fluid actuated member reciprocable therein, said member having a duality of heads in fluid tight engagement with the inner wall of

5 said tube, a stationary partition between said heads having a rod slidable therethrough uniting said heads, passages for admitting motive fluid into said tube adjacent said partition for actuating said member, a flexible draft element connecting said member to said motor, said element being fastened to said tube and said motor while engaging said member for movement relative thereto during the normal reciprocation of the latter, and openings through said tube through which said element is free to pass from the interior to the exterior of said tube, the position of said openings being such that the motive fluid admitted into said tube is prevented to escape 10 through said openings due to the fluid tight engagement of the heads of said member with the inner wall of said tube irrespective of the position of the former within the latter.

2. In a rock drilling apparatus, a support having a drilling motor slidably guided thereon, a feeding mechanism for said motor comprising a tube having a power actuated member movable back and forth therein, a duality of heads for said members in fluid tight engagement with the inner wall of said tube, a partition between said heads having a rod slidable therethrough uniting said heads, means for admitting pressure fluid into said tube adjacent said partition for actuating said member, a flexible draft element connecting said member to said motor, rotatable bodies carried by said member and tube, said flexible element while located within said tube extending from one end thereof where it is fastened toward said member for passing around 25 one of said bodies carried thereby and back toward the end of said tube for passing around another of said bodies carried by the latter from where it extends externally of said tube to the motor where it is fastened, and at least one opening through said tube through which said flexible element is free to pass from the interior to the exterior thereof, the rotatable body carried by said tube being located relatively to said opening in a manner affording said flexible element to 30 remain in spaced relation with the wall of said tube.

3. In a rock drilling apparatus, a support having a drilling motor slidably guided thereon, feeding means for said motor comprising a tube having a power actuated member slidable therein in both directions, a duality of heads for said members in fluid tight engagement with the inner wall of said tube, a partition between said heads having a rod slidable therethrough uniting said heads, means for admitting pressure fluid into said tube adjacent said partition for actuating said member, a mechanism for transmitting the movement of said member in one direction to said motor including a flexible element fastened to said motor and to one end of said tube, a duality of rotatable bodies one carried by said tube and the other carried by said member, said flexible element leading from said motor rearwardly over said first mentioned body, then forwardly over the body carried by said member and thereafter rearwardly to said one end of the tube, said rotatable bodies being located to maintain the portion of said flexible element extending therebetween substantially parallel with the portions extending therefrom to said motor and to said one end of the tube, two of said portions being located within said tube while the other is located externally thereof, an open-

5 ing through which said element is free to pass from the interior to the exterior of the tube, and means for transmitting the movement of said member in the other direction to said motor, said last means being a replica of said mechanism.

4. In a drilling apparatus, a support having a drilling motor slidably guided relatively thereto, feeding means for said motor including a feed tube formed with two piston chambers having a 10 partition therebetween, a piston within each of said chambers reciprocable therein, a rod through said partition uniting said pistons, means for admitting pressure fluid into said chambers adjacent said partition for actuating said pistons, a mechanism associated with said pistons and motor for transforming the movement of the former to the latter at a multiplied rate of speed, said mechanism including a system of pulleys of the whip and runner type, and an opening 15 through said tube through which the whip or flexible element incorporated in said system is free to pass from the interior of the tube where it is affixed to the exterior thereof where it is secured to said motor. 25

5. In a drilling apparatus, a support having a drilling motor slidably relatively thereto, feeding means for said motor comprising a tube having a member slidable therein in both directions, a duality of heads for said member in fluid tight 20 engagement with the inner wall of said tube, a stationary partition between said heads having a rod slidable therethrough uniting said heads, means for admitting pressure fluid between said heads adjacent said partition for actuating said 25 member, a mechanism associated with said member and motor for transmitting the movement of the former to the latter at a greater rate of speed, said mechanism including a system of pulleys of the whip and runner type, one end of 40 the whip or flexible element being affixed to the support and the other to the motor, the runner being carried by said member for movement therewith, and an opening leading from the interior of said tube to the exterior thereof through 45 which the whip is free to pass.

6. In a drilling apparatus, a support having a drilling motor longitudinally slidably relatively thereto, feeding means for said motor comprising a duality of coaxial piston chambers within said 50 support having a partition therebetween, a piston within each of said chambers for longitudinal slidable movement therein in both directions, a rod slidable through said partition uniting said pistons, means for admitting pressure 55 fluid into said chambers adjacent said partition for actuating said pistons, a mechanism for transmitting the movement of said pistons in one direction to said motor, said mechanism including a system of pulleys of the whip and runner type, one end of the whip or flexible element incorporated in said system being affixed to said support and the other end to said motor, the runner or longitudinally movable pulley being 60 carried by one of said pistons for movement therewith, an opening through said support through which the flexible member is free to pass from the interior to the exterior thereof, and means for transmitting the movement of said pistons in the other direction to said motor, said last means being a replica of said mechanism. 65

70 JOHN C. CURTIS.
